ALTERNATING-CURRENT MOTOR METER

Application filed August 20, 1924. Serial No. 733,049.

My invention relates to alternating-current apparatus and particularly to motor meters of the induction type.

One object of my invention is to provide a wattmeter, relay or watthour meter of the induction type that shall be exceptionally accurate over a wide range of current, voltage and frequency.

Another object of my invention is to provide an improved method of forming the laminated core member of an instrument of the induction type.

In the accompanying drawing

Figure 1 is a view of an alternating-current motor of the induction type to which my invention is applicable; and

Fig. 2 is a plan view of a modified form of lamination.

Referring to Fig. 1, a motor 1 for a wattmeter or relay comprises a magnetizable core member 2, energizing means therefor in the form of series and shunt windings 3 and 4, and a pivoted armature 5 cooperating with said core member.

25 The core member 2 is constructed of flat or plane sheets or laminations having an outer perimetral portion or closed-magnetic circuit in the form of a closed loop. The elongated shunt pole portion on which the voltage winding 3 is disposed, extends inwardly from the loop and is provided with free-end extensions 15 which are paired in slightly spaced parallel side-edge relation to portions 14 supported at, and extending inwardly 30 from, the loop through the intermediary of the transverse portion having the dimension 9.

When the series and shunt windings 3 and 4 are energized, alternating magnetic fluxes traverse the edge of the armature 5 and produce a torque thereon, the magnitude and direction of which depend upon the magnitude and direction of the currents in the windings and upon the character and location of the core member 2. The instrument 1 may be 45 an integrating or indicating wattmeter or a relay, depending upon the elements controlled by the armature 5. As the specific character of these elements is not essential to my invention and such elements are well known, 50 they are not shown.

It is desirable that the torque on the armature 5 be exactly proportional to the power traversing the instrument, or to $EI \cos \phi$ over a wide range of voltage, current, power factor and frequency. This is especially 55 true of integrating watthour meters where a high standard of accuracy is required.

Since the voltage and frequency supplied to a watthour meter in service are maintained substantially constant, these characteristics 60 have always been ignored and the instruments built to read correctly for variations of current and power factor only. The effect of increasing the voltage applied to the shunt winding 4 is to cause increased damping of 65 the armature 5 and, therefore, the instrument to read low as the voltage is increased and the power kept constant. It is possible, however, to so modify the relation of the magnetic paths of the flux produced by the shunt 70 winding traversing the disc that an increased torque is obtained that compensates for the normally increased damping effect.

Theoretically, the induction-type wattmeter is independent of variations of frequency at unity power factor but actually the increased reactance of the windings causes a diminished torque when the frequency is increased and the power kept constant. It is possible to compensate for this also by modifying the magnetic paths of the flux produced by the shunt winding. The compensation for voltage and frequency each slightly affects 75 the other adjustment but it is possible to make a change that is a compromise so that 80 the instrument will be substantially accurate 85 for variations in both voltage and frequency.

As shown in Fig. 1, the flux produced by the shunt winding 4 has three distinct paths 6, 7 and 8. The flux of the path 6 does not 90 traverse the armature 5 and, therefore, does not affect the operation of the instrument. The fluxes of the paths 7 and 8 both traverse the armature 5 and, therefore, the fluxes following these paths exert a torque on 95 said armature. Changing the dimension 9 of the core laminations varies the relative reluctance of the three paths 6, 7 and 8 and this change varies the voltage characteristic, or flux variation caused by voltage varia- 100

tions, of the instrument so that either a flat, a drooping or a rising characteristic may be obtained. Changing the dimension 10 of the core laminations also varies the relative reluctance of the paths 7 and 8 and I have found that this change varies the frequency characteristic, or flux variation caused by frequency variations, of the meter so that this characteristic may be made either flat, drooping or rising, as desired. Changing either of the dimensions 9 and 10 changes both the voltage and frequency characteristics to some extent but, since each affects one characteristic more than the other, it is possible to compromise upon the changes so that the desired voltage and frequency characteristics may both be obtained.

In Fig. 2 is shown a modified form of a one-piece core lamination suitable for a watt-hour meter in which the accuracy is not affected by changes in voltage and frequency. The lamination 11 is a punching of sheet steel. In order to obtain these laminations in large quantities and of accurate dimensions they are punched from sheet metal with accurate dies. These dies are expensive and, consequently, it is not possible, from a practical standpoint, to alter any of the dimensions of the punching after the dies have been made, on account of the expense involved.

In order to practice my invention, the lamination 11 is punched out in approximately the desired form with an excess of material in the pole pieces and yokes. It is not practicable to obtain a lamination having exactly the desired characteristics because of the intricate form of the punching and the many factors involved. Accordingly, the punchings 11 are subsequently perforated at 12 and 13 to modify the voltage and frequency characteristics thereof, as desired.

While the perforations 13 are indicated as approximately circular and as extending through each of the portions 14 and 15, they are so provided merely as a matter of manufacturing facility and to avoid the removal of an excess of material from the portions 15, the purpose being to constrict the portions 15. In other words, while the extensions 15 may be locally constricted or proportioned in any desired manner, it has been found to be a matter of manufacturing facility and structural effectiveness to constrict the portion 15 by the use of a tool of symmetrical cross-sectional contour that is driven normal to the plane of the core along a center point or line preferably in the space between the portions 14 and 15, it being immaterial that a portion of the extension 14 is thereby also removed.

It is a simple matter to determine experimentally the dimensions of the perforations 12 and 13 that will provide flat frequency and voltage characteristics by testing instruments in which various sizes of perforations have been formed.

For example, increasing the size of the perforations 12 tends to flatten the normally drooping voltage characteristic curve of the meter, and increasing the size of the perforations 13 corrects the normally drooping frequency characteristic curve. As above indicated, these perforations may be independently progressively increased in size until a flat or rising frequency or voltage characteristic curve is obtained. Actually, however, alteration in the size of either the perforations 12 or that of the perforations 13 affects both the voltage and frequency characteristics. It is necessary, therefore, to so proportion the size of the perforations that a compromise is effected whereby the voltage and frequency characteristic curves approach a desired straight-line condition and are substantially flat.

When the sizes of the perforations 12 and 13 have once been determined for a given lamination, the proper perforation of additional laminations may readily be accomplished.

Another advantage of this method of forming the laminations is that the projecting portions 14 and 15 of the laminations are mechanically stronger when they are perforated, as at 12 and 13, instead of the portions 14 and 15 being reduced in width sufficiently to provide the desired characteristics.

The flux of the path 7 is instantaneously bidirectional through the armature 5 and the flux of the path 8 is instantaneously unidirectional through the armature. Also, the local constrictions in the portions adjacent to the dimensions 9 and 10, caused by the perforations or recesses 12 and 13, respectively, so proportion these portions that the relative reluctances of the paths 7 and 8, and consequently the flux distribution thereof, are such as will approximately avoid error in the registration of the instrument caused by frequency and voltage variation between predetermined limits. In other words, the ratio of the values of the instantaneously unidirectional flux of the path 8 to the values of the instantaneously bidirectional flux of the path 7 is increased between predetermined limits of flux variation and diminished for variations beyond such limits.

While I have illustrated and described my invention as applied to a core member composed of one-piece laminations I consider that it is applicable to other forms of laminations. The laminations may be perforated subsequently, as I have stated, or the dies may be so modified as to perforate the laminations in the original punching operation. Furthermore, my invention may be applied to either wattmeters or relays and may be utilized to provide such instruments with either drooping or rising voltage and frequency characteristics, as well as a flat characteristic. Accordingly, I do not wish to be

limited to the precise form of my invention shown and described, as this description is for the purpose of exemplification only.

I claim as my invention:

- 5 1. In an electric motor meter, the combination with an armature and energizing means, of a core co-operating between the energizing means and the armature having pole portions and providing an armature gap and paths for 70 alternating fluxes one of which is instantaneously unidirectional through the armature and another of which is instantaneously bidirectional through the armature, the reluctance of said paths being such as to cause such 75 relative flux distribution in said paths as will substantially avoid error in registration caused by frequency and voltage variation between predetermined limits.
2. In an electric motor meter, the combination with an armature and energizing means, of a core co-operating between the energizing means and the armature having pole portions providing an armature gap and paths for alternating fluxes one of which is instantaneously unidirectional through the armature and another of which is instantaneously bidirectional through the armature, portions 80 of said core being proportioned to increase the ratio of unidirectional flux values to bidirectional flux values between predetermined limits of flux change and to diminish that ratio for variations beyond said limits.
3. In an electric motor meter, the combination with an armature and energizing means, of a core co-operating between the energizing means and the armature having pole portions providing an armature gap and paths for alternating fluxes one of which is instantaneously unidirectional through the armature and another of which is instantaneously bidirectional through the armature, the core having locally constricted portions to cause such relative flux distribution in said paths as will substantially avoid error in registration 90 caused by frequency and voltage variations between predetermined limits.
4. In an electric motor meter, the combination with an armature and energizing means, of a core co-operating between the energizing means and the armature having pole portions providing an armature gap and paths for alternating fluxes one of which is instantaneously unidirectional through the armature and another of which is instantaneously bidirectional through the armature, the core having locally constricted portions to increase the ratio of unidirectional flux values to bidirectional flux values between predetermined limits of flux change and to diminish 95 that ratio for variations beyond said limits.
5. In an electric motor meter, the combination with an armature and energizing means, of an alternating-flux field-magnet core co-operating between the energizing means and the armature comprising a closed loop, a pole 100 portion projecting inwardly therefrom, portions projecting inwardly from the loop to positions adjacent to opposite sides of said pole portion and pole portions projecting from the loop and extending substantially parallel to said first pole portion, each including a local portion of constricted cross-sectional area controlling the operating flux in predetermined manner.
6. In an electric motor meter, the combination with an armature and energizing means, of an alternating-flux plane laminated field-magnet core co-operating between the energizing means and the armature comprising a closed loop, an elongated pole portion projecting inwardly from said loop, a pair of portions extending from the free end of said pole portion, portions projecting transversely of said pole portions and inwardly from the loop to positions adjacent opposite sides of the pole portion, and extensions of said transverse portions extending from positions adjacent to the inner ends thereof each in slightly-spaced parallel side-edge relation to one of said pole-portion extensions, said transverse 105 portions each having a local portion of constricted cross-sectional area to control the effect of variations of the core flux.
7. In an electric motor meter, the combination with an armature and energizing means, of an alternating-flux field-magnet core co-operating between the energizing means and the armature comprising stacked flat laminations providing a closed loop, an elongated pole portion projecting inwardly from said loop, a pair of portions extending from the free end of said pole portion each having a local portion constricted in cross-sectional area to control the effect of variations of the core 110 flux, and portions projecting transversely of said pole portion and inwardly from the loop, each having an extension paired with one of said pole-portion extensions in slightly-spaced parallel side-edge relation thereto.
8. In an electric motor meter, the combination with an armature and energizing means, of an alternating-flux plane-laminated field-magnet core co-operating between the energizing means and the armature comprising a closed loop, an elongated pole portion projecting inwardly from said loop, a pair of portions extending from the free end of said pole portion, each having a local portion constricted in cross-sectional area to control the effect of variations of the core flux, portions 115 projecting transversely of said pole portion and inwardly from the loop to positions adjacent opposite sides of the pole portion and each having a local portion of constricted cross-sectional area to control the effect of variations of the core flux, portions 120 projecting transversely of said pole portion and inwardly from the loop to positions adjacent opposite sides of the pole portion and each having a local portion of constricted cross-sectional area to control the effect of variations of the core flux, and extensions of said transverse portions extending from positions adjacent to the inner ends thereof each in slightly-spaced parallel side-edge relation to one of said pole-portion extensions.
- 125

9. In an electric motor meter, the combination with an armature and energizing means, of an alternating-flux plane laminated field-magnet core co-operating between the energizing means and the armature comprising a closed loop, an elongated pole portion projecting inwardly from said loop having longitudinal free-end extensions, and portions projecting transversely of said pole portion and inwardly from the loop, each having an extension longitudinally of said pole portion paired with one of said first extensions in slightly-spaced parallel side-edge relation thereto, one edge of each of said pairs having a recessed portion.
10. In an electric motor meter, the combination with an armature and energizing means, of an alternating-flux plane laminated field-magnet core co-operating between the energizing means and the armature comprising a closed loop, an elongated pole portion projecting inwardly from said loop having longitudinal free-end extensions, and portions projecting transversely of said pole portion and inwardly from the loop, each having an extension longitudinally of said pole portion paired with one of said first extensions in slightly-spaced parallel side-edge relation thereto, each of said edges having normal to the plane of the core a recessed portion the outline of which in said plane is disposed symmetrically about a center point about which the outline of the next adjacent recessed portion is symmetrically disposed.
- 35 In testimony whereof, I have hereunto subscribed my name this 18th day of August, 1924.
